(57) **CLAIM**

I claim the ornamental design for a scissor type automotive lift, as shown and described.

DESCRIPTION

FIG. 1 is a front right perspective view of a scissor type automotive lift in the extended position, showing our new design;

FIG. 2 is a side plan view thereof;

FIG. 3 is a front plan view thereof;

FIG. 4 is a rear plan view thereof;

FIG. 5 is top right perspective view thereof; and,

FIG. 6 is a front left perspective view thereof.

The bottom of the lift is not part of the claim design.
